UNITED STATES PATENT OFFICE

138,730

DESIGN FOR A PIPE REST

Benjamin E. Lawrence, Chicago, Ill.

Application May 29, 1944, Serial No. 113,791

Term of patent 3½ years

(Cl. D85—2)

To all whom it may concern:

Be it known that I, Benjamin E. Lawrence, a citizen of the United States, residing at Chicago, in the county of Cook and State of Illinois, have invented a new, original, and ornamental Design for a Pipe Rest, of which the following is a specification, reference being had to the accompanying drawing, forming a part thereof.

In the drawing—

Fig. 1 is a perspective view looking toward the front and right side of the pipe rest, showing my new design, and

Fig. 2 is a perspective view looking toward the rear and left side of the pipe rest.

I claim:

The ornamental design for a pipe rest, as shown.

BENJAMIN E. LAWRENCE.
